United States Patent Office

Des. 228,930

Patented Oct. 30, 1973

228,930

GOLF PUTTER

Robert G. Leigh, 6 Stoecher Lane, Holmdel Township,
Monmouth County, N.J. 07733

Filed May 23, 1972, Ser. No. 256,200

Term of patent 14 years

Int. Cl. D21—02

U.S. Cl. D34—5 GC

FIG. 1

FIG. 2

FIG. 1 is a perspective view of the golf putter in front elevation; and

FIG. 2 is a perspective view of the golf putter in rear elevation with the shaft shown fragmentarily for convenience of illustration.

I claim:

The ornamental design for a golf putter, as shown and described.
